UNITED STATES PATENT OFFICE.

GEORGE McCADDEN, OF ST. CLOUD, MINNESOTA.

LABEL-AFFIXER.

SPECIFICATION forming part of Letters Patent No. 623,330, dated April 18, 1899.

Application filed February 26, 1898. Serial No. 671,836. (No model.)

To all whom it may concern:

Be it known that I, GEORGE McCADDEN, a citizen of the United States, residing at St. Cloud, in the county of Stearns and State of Minnesota, have invented certain new and useful Improvements in Automatic Label-Affixers, of which the following is a specification.

My invention relates to improvements in automatic label-affixers, and has for its object 10 to provide a simple, cheap, light, easily-manipulated, but strong and durable device which at one-motion cuts off the label, affixes it to the desired object, and brings another into place ready for the next stroke. This 15 object I accomplish in the manner and by the means hereinafter fully described in detail, and particularly pointed out in the claims, reference being had to the accompanying drawings, in which like reference-letters indicate like parts in all the figures.

Figure 1 is a side elevation of my invention. Fig. 2 is a rear elevation of my invention, partly cut away. Fig. 3 is a detail view of 25 two cutters. Fig. 4 is a detail view of feed-roller and spring in section. Fig. 5 is a detail view of ring and end of feed-shaft.

My invention consists of a box or body A of any suitable material, preferably aluminium, cast in one piece and closed at the top, 30 front, and two sides, leaving the bottom and rear open. Arms B of any suitable material, preferably aluminium, are arranged one on each side of said body A and adapted to slide up and down. The tops of the arms B are 35 connected by the yoke C, made integral with said arms B, and from the center of which yoke C rises a hollow handle D, and in said hollow handle D a spiral spring d is placed. A guiding-rod a is secured to the top of the 40 body A and extending through the center of the yoke C into the handle D.

On each side of the body A, near the top, are guides a', secured to the body A or made integral therewith, between which guides a' 45 the arms B move. On each side of the body A, near the bottom and toward the rear, an arm E has one end pivotally secured. The arms E normally extend diagonally upward and are connected with the free ends of the 50 arms B by means of screws or other suitable devices working in the slots e in the arms E.

The free ends of the arms E are bent slightly downward and are connected by a yoke F, made integral with said arms E, the face of said yoke F being normally inclined at an angle to the surface on which the body A rests. 55 To the yoke F is secured the cutter and foot G by screws H or other suitable means allowing of adjustment. The cutter and foot G has its cutting edge downward and its face 60 inclined at such an angle to the surface on which the body A rests that when pressed down its face rests flat upon the label.

The front of the body A, near the bottom, is cut away to receive the lower cutter I, and 65 just above where the front is so cut away a slot i, running diagonally, is cut. The lower cutter I is formed of a plate bent at right angles and secured by the lower part to the body A by screws or other suitable devices, the upper part forming a diagonally-inclined shelf i' just under the slot i, at the outer edge of which shelf i' is the cutting edge.

Inside of each side of the body A and at a suitable distance from the top is a small 70 groove a², running from the rear to the center of said side, where it ends in a small hole. A roller J, adapted to have the strip containing the labels or other matter rolled on it, is 75 mounted on a spring-axle, the ends of which are pointed and may be slightly compressed. The pointed ends of the axle of the roller J being inserted in the grooves a², a slight pressure will cause them to pass along said grooves a² to the holes at the ends of said grooves a². 80 Below said roller J is another roller K, consisting of soft india-rubber drawn over a metal sleeve. The roller K is the feed-roller and is mounted on a shaft L, to which it is keyed, and one end of which shaft L is journaled in the side of the body A and extends 85 beyond it and is provided with a small wheel or other means by which the roller K may be revolved by hand. The other end of said shaft L is journaled in the side of the body 90 A. A circular recess M is cut in the outside of the side of the body A around the end of the shaft L. In said recess M a steel ring m fits, said ring m being provided on its inner surface with recesses m', in which pieces of 95 spring-steel m² are placed, so that their free ends bear on the shaft L in a positive direc- 100

tion and are held against said shaft L by pieces of rubber m^3 , inserted in said recesses m' . In the inner surface of said ring m are notches m^4 , in which balls work. Covering 5 said ring m and filling said recess M is a thin steel disk m^5 , through a hole in which a pin m^6 is fixed in said ring m and extends into a slot b in the end of the arm B. On the inside of the front of said body A a spring k is 10 secured, which rests on said roller K and retards its revolving in negative direction. Also on the inside of the front of the body A, just above the slot i , are secured a thin plate k' , of metal or other suitable material, which 15 extends to the lower side of the roller K, and fingers k^2 , extending through the slot i and upon the lower cutter I to hold the strip of labels. A pot N, of any suitable material, preferably thin metal, and adapted to fit in 20 the bottom of the body A, under the roller K, contains the paste or other adhesive substance and is covered over in front and raised toward one side to aid in directing the strip of labels through the slot i . A roller O, of 25 hard wood or other suitable material, is mounted on a shaft, the ends of which are journaled in slots in plates fixed to the sides of said pot N just back of the covered part, and when said pot N is in place said roller O is in contact 30 with the roller K and is turned by friction. The bottom of the body A is closed by a plate a^8 , on which the pot N rests and against which the spring n , fixed on the bottom of the pot N, bears. Just at the top of the slot b on the 35 arm B is secured a slotted sleeve b' by a screw or other suitable means through the slot. The rod b^2 connects the top of the sleeve b' with the short arm of the lever b^3 , to which it is 40 pivotally secured. The lever b^3 is fulcrumed near the top of the arm B and bent so as to stand nearly upright when the sleeve b' is lowered. The sleeve b' regulates the length 45 of the slot b , in which the pin m^6 works. By means of the lever b^3 and the connecting-rod b^2 the sleeve b' can be moved up or down along the arm B, and the lower edge of the sleeve b' , engaging the pin m^6 , controls the revolution 50 of the ring m in order to feed labels of different widths for cutting.

50 The operation of my invention is as follows: The strip of labels is wound upon the roller J, the roller J inserted into its place, and the end of the strip inserted between the rollers K and O. The pot N, filled with paste, is placed 55 in the bottom of the body A, and the machine is ready for work. As the handle D is pressed down, the ends of the arms B carry the arms E downward, the screws connecting said arms B and E sliding in the slots e , and the cutter G 60 is brought down on the strip of labels at the lower cutter's edge I in a shearing manner, cutting off a label, and at the same time the face of the cutter G is pressed on the label as a stamp to secure it to the paper. The spiral 65 spring d causes the handle D to rise again, and as it does the lower edge of the slot b engages the pin m^6 , revolves the disk M, carry-

ing the shaft L, and feeds the label strip which the roller O has supplied with paste to the cutter. 70

Having thus described my invention, what I claim as new, and desire to secure by Letters Patent, is—

1. An automatic label-affixer consisting of a frame carrying the label, feed and paste 75 rollers, an arm on each side said frame, having one end pivotally secured to said frame and extending forward and beyond said frame, a cutter and foot secured to the outer ends of said arms and means for operating 80 the same, substantially as shown and described.

2. An automatic label-affixer consisting of a frame carrying the label, feed and paste rollers, an arm on each side said frame, having 85 one end pivotally secured to said frame and extending forward and beyond said frame, a cutter and foot secured to the outer ends of said arms, a metal plate secured to the front of said frame near the bottom and bent outward at right angles to form a shelf inclining 90 diagonally upward across the front of said frame, the outer edge of said shelf forming the cutting edge and means for operating the same, substantially as shown and described. 95

3. An automatic label-affixer consisting of a frame, label and feed rollers mounted in said frame, a paste-pot with a paste-roller mounted in it and a forked arm astride said frame, one fork provided near its end with a 100 slot, a slotted sleeve secured to said fork and adapted to partially close the slot in said fork, a lever fulcrumed near the top of said fork, and a rod connecting said sleeve and the short arm of said lever, substantially as shown and 105 described.

4. An automatic label-affixer consisting of a frame, label and feed rollers mounted in said frame one vertically over the other, and a paste-pot at the bottom of said frame carrying a paste-roller, a ring having recesses in its interior face, pieces of spring-steel secured at one end in said recesses and pressing at the other end in a positive direction on the shaft carrying the feed-roller, and means for 110 operating same, substantially as shown and described.

5. An automatic label-affixer, consisting of a frame, label and feed rollers mounted in said frame one vertically over the other, and a paste-pot at the bottom of said frame carrying a paste-roller, a ring having a pin on its outer face and recesses in its interior face, pieces of spring-steel secured at one end in 120 said recesses and pressing at the other end in 125 a positive direction on the shaft carrying the feed-roller, a forked handle astride said frame and provided at the end of one of its forks with a slot adapted to engage said pin, and means for operating same, substantially as 130 shown and described.

6. An automatic label-affixer, consisting of a frame, label and feed rollers mounted in said frame, one vertically over the other, and

a paste-pot at the bottom of said frame carrying a paste-roller, a ring having a pin on its outer face and recesses in its interior face, pieces of spring-steel secured at one end in 5 said recesses and pressing at the other end in a positive direction on the shaft carrying the feed-roller, a forked handle astride said frame and provided at the end of one of its forks with a slot adapted to engage said pin, 10 arms pivotally secured at one end to the sides of said frame and at the other to the cutter and foot, said arms provided with slots in which screws in the ends of the handle-forks move, substantially as shown and de- 15 scribed.

7. An automatic label-affixer, consisting of a hollow wedge-shaped box; a label-roller mounted on an endwise-compressible axle journaled in said box; a feed-roller on a shaft 20 journaled at one end in said box and at the other in a steel ring; a spring secured to the front of said box and resting on said feed-roller; a paste-pot covered over in front fitting in the bottom of said box; a paste- 25 roller journaled in said paste-pot; a steel ring fitting in the side of said box; said ring having on its outer surface a pin and in its interior surface recesses pieces of spring-steel secured at one end in said recesses and

bearing at the other end in a positive direction on the feed-roller shaft; a hollow handle mounted on a forked arm; a spring in said hollow handle; a guiding-rod secured to the top of said box and adapted to enter said handle; a forked arm adapted to slide up and down the 35 sides of said box, one fork of said arm provided with a slot adapted to receive the pin on said ring; a slotted sleeve secured to said fork and adapted to partially close said slot, a lever fulcrumed near the top of said fork; a rod 40 connecting said sleeve and the short arm of said lever; arms pivotally secured at one end to the sides of said box near the bottom and having their other ends connected by a yoke, 45 said arms provided with slots in which screws secured in the ends of said forks work; a cutter and foot adjustably secured to said yoke; a cutter secured to the front of said box inclined diagonally upward, and a guide secured to said box and resting against the bottom of said feed-roll, substantially as shown and described.

In testimony whereof I hereto affix my signature in the presence of two witnesses.

GEORGE McCADDEN.
